HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,241,923.

Specification of Letters Patent.

Patented Oct. 2, 1917.

Application filed February 19, 1916. Serial No. 79,439.

To all whom it may concern:

Be it known that I, HENRY P. CLAUSEN, a citizen of the United States, residing at Mount Vernon, in the county of Westchester and State of New York, have invented certain new and useful Improvements in Telephone-Exchange Systems, of which the following is a full, clear, concise, and exact description.

10 This invention relates to telephone exchange systems, and more particularly to such systems of the central energy type.

The object of this invention is to provide improved signaling means for such systems.

15 In central offices, considerable time is wasted by operators listening in on a cord circuit when only one supervisory signal is displayed, the operator assuming that a subscriber is waiting, when the non-coincident 20 occurrence of both supervisory signals is due to one of the parties to the connection restoring his receiver to the switchhook more promptly than the other party.

In accordance with this invention, the 25 usual link circuit having a signaling device associated with each end thereof is provided with apparatus for causing the simultaneous operation of the signaling devices to furnish disconnect signals, when 30 both subscribers have restored their receivers to the switchhooks.

This invention will be fully understood from the following description and the accompanying drawing, in which all apparatus is shown in its normal or unactuated 35 condition.

There is shown in the drawing, a telephone exchange system comprising subscribers' stations A and B terminating at a 40 central office, and a cord circuit C located thereat for interconnecting the subscriber's station.

Subscriber A, wishing to converse with subscriber B, removes the receiver from the 45 switchhook, thereby causing the display of line signal 10, which is effected in a well-known manner. The operator, upon observing line signal 10, inserts the answering plug into the jack indicated by the line signal, thereby causing the operation of relay 11 and cutoff relay 13 over a circuit from battery through the winding of relay 11, sleeve contacts of the answering plug and jack and the winding of cutoff relay 13 to 50 ground. Cutoff relay 13 in operating causes line lamp 10 to be extinguished. The insertion of the answering plug in the jack also causes the operation of supervisory relay 12, over a circuit from battery through the winding of relay 11, ring contacts of 55 the answering plug and jack, one side of the line, substation apparatus, the other side of the line, tip contacts of the jack and answering plug and the winding of supervisory relay 12 to ground. The operation of relay 12 opens the normal contact thereof, preventing the lighting of supervisory lamp 14.

The operator then actuates listening key 15, connecting the operator's telephone set 70 across the talking strands of the cord circuit, and asks the desired number of the calling subscriber. Upon learning the desired number to be that of subscriber B, the operator inserts the calling plug into 75 the jack of B's line, thereby causing the operation of relay 16 and cutoff relay 17 over a circuit from battery through the winding of relay 16, sleeve contacts of the calling plug and jack and the winding of 80 cutoff relay 17 to ground. The operation of relay 16 causes the lighting of supervisory lamp 18 over a circuit from battery through the right hand normal contact of slow release relay 19, lamp 18, normal contact 85 of relay 20 and contact of relay 16 to ground. The operator now restores the listening key 15 to its normal position and actuates ringing key 21, connecting a source of ringing current 22 to the called subscriber's line to 90 actuate the call bell 23. After ringing the called subscriber the operator restores the ringing key 21 to its normal position. In response to the sounding of call bell 23 due to the passage of current therethrough, subscriber B removes the receiver from the 95 switchhook, thereby causing the operation of supervisory relay 20 over a circuit from battery through the winding of relay 16, ring contacts of the calling plug and jack, one side of the line, substation apparatus, the other side of the line, tip contacts of the jack and calling plug and the winding of relay 20 to ground. Relay 20, in operating, effaces supervisory signal 18, indicating to the operator that subscriber B has answered. The operation of relay 20 also causes the operation of slow release relay 19, over a circuit from battery through contact of relay 11, alternate contact of relay 110

12, winding of relay 19, alternate contact of relay 20, and contact of relay 16 to ground.

Assume now that subscribers A and B complete their conversation and A restores his receiver to the switchhook first, relay 12 releases, thereby closing one break in the circuit through to supervisory lamp 14. The opening of the alternate contact of relay 12 opens the circuit through the winding of slow-release relay 19, but owing to the structure of relay 19, the alternate contacts thereof are not opened and the normal contacts thereof are not closed until after a definite predetermined time.

Should B restore his receiver to the switchhook after A, but before relay 19 releases, both supervisory lamps will be caused to light in synchronism upon the restoration of B's receiver to the switchhook, the circuit for both lamps being from battery through the contact of relay 11, normal contact of relay 12 where it branches, one branch being through lamp 14, left-hand alternate contact of relay 19 to normal contact of relay 20 and the other branch being through the right hand alternate contact of relay 19 and the lamp 18 to normal contact of relay 20 and thence through contact of relay 16 to ground. If, however, B restores his receiver to the switchhook after A and simultaneously with the falling off of relay 19, both lamps will be caused to light in synchronism, but over different circuits from those just traced. The circuit through lamp 14 may then be traced from battery through contact of relay 11, normal contact of relay 12, supervisory lamp 14 and left-hand normal contact of relay 19 to ground, and the circuit through lamp 18 may then be traced from battery through right-hand normal contact of relay 19, supervisory lamp 18, normal contact of relay 20 and contact of relay 16 to ground.

The display of supervisory signals 14 and 18 in synchronism indicates to the operator that both subscribers have completed their conversation and restored their receivers to the switchhooks, whereupon the operator will respond by withdrawing the answering and calling plugs from the jacks, thereby disconnecting the two subscribers.

From the above it will be seen that neither of the supervisory lamps will be caused to light until relay 19 releases.

To prevent the passage of battery from one end of the cord circuit to the other, condensers 24 and 25 are included in the tip and ring conductors of the cord circuit.

In telephone exchange systems prior to this invention, whenever two subscribers were in conversation over telephone lines interconnected at a central office, and one subscriber restored his receiver to the switchhook more promptly than the other, one of the supervisory lamps would be

caused to light immediately upon the restoration of the first receiver to the switchhook, while the other supervisory lamp would not be lighted until the other subscriber restored his receiver to the switchhook, thereby resulting in an interval when only one of the disconnect signals would be displayed. Statistics which have recently been compiled show that out of the total number of calls responded to by the operators, from ten to twenty-five per cent. are due to the non-coincident occurrence of the disconnect signals. Therefore, it will readily be seen that by means of this invention, whereby the supervisory signals associated with the answering and calling ends of the cord circuit are not lighted to give a disconnect signal until after the expiration of a predetermined period of time which should be sufficient for both subscribers to have restored their receivers to the switchhook, the time wasted by the operators entering upon a cord circuit when only one signal thereof is displayed is avoided.

What is claimed is:

1. In a telephone system, telephone lines terminating at a central office, a link circuit thereat for interconnecting said lines, a supervisory signaling device associated with each end of the link circuit, and a slow release relay jointly controlled from the connected telephone lines to cause the simultaneous operation of the signaling devices when the receiver of one of the connected telephone lines is restored to the switchhook within a predetermined time after the other is restored.

2. In a telephone system, telephone lines terminating at a central office, a link circuit thereat for interconnecting said lines, a supervisory signaling device associated with each end of the link circuit, a supervisory relay associated with each end of the link circuit controlled over the respective connected telephone lines, and means jointly controlled by and coöperating with the supervisory relays to cause the simultaneous operation of the signaling devices when the receiver of one of the connected telephone lines is restored to the switchhook within a predetermined time after the other is restored.

3. In a telephone system, telephone lines terminating at a central office, a link circuit thereat for interconnecting said lines, a supervisory signaling device associated with each end of the link circuit, a supervisory relay associated with each end of the link circuit controlled over the respective connected telephone lines, and a slow release relay jointly controlled by and coöperating with the supervisory relays to cause the simultaneous operation of the signaling devices when the receiver of one of the con-

nected telephone lines is restored to the switchhook within a predetermined time after the other is restored.

4. In a telephone system, telephone lines terminating at a central office, a link circuit thereat for interconnecting said lines, a supervisory signaling device associated with each end of the link circuit, means associated with each end of the link circuit controlled over the respective connected telephone lines, and means jointly controlled by and coöperating with the aforesaid means to cause the simultaneous operation of the signaling devices when the receiver of one of the connected telephone lines is restored to the switchhook within a predetermined time after the other is restored.
5. In a telephone system, telephone lines terminating at a central office, a link circuit thereat for interconnecting said lines, a supervisory signaling device associated with each end of said link circuit, and switching means jointly controlled from each of the connected lines for delaying for a predetermined period the operation of one of the signaling devices upon the restoration to the

switchhook of the receiver on one of the connected lines and for causing the simultaneous operation of the signaling devices when the receiver of the other connected line is restored to the switchhook within the predetermined period.

6. In a telephone system, telephone lines terminating at a central office, a link circuit thereat for interconnecting said lines, a supervisory signaling device associated with each end of said link circuit, a supervisory relay associated with each end of said link circuit controlled over the respective connected telephone lines, and a switching device jointly controlled by and coöperating with the supervisory relays for delaying for a predetermined period the operation of one signaling device upon the opening of one line circuit, and for causing the simultaneous operation of both signaling devices when the other line circuit is opened within the predetermined period.

In witness whereof, I hereunto subscribe my name this 16th day of February A. D., 1916.

HENRY P. CLAUSEN.
